DESIGN FOR A PILLOWCASE OR SIMILAR ARTICLE

Nettie Robinson, New York, N. Y.

Application October 2, 1940, Serial No. 95,583

Term of patent 3½ years

To all whom it may concern:

Be it known that I, Nettie Robinson, a citizen of the United States and residing in the Borough and county of Bronx, city and State of New York, have invented a new, original, and ornamental Design for a Pillowcase or Similar Article, of which the following is a specification, reference being had to the accompanying drawing, forming part thereof, wherein

Fig. 1 is a front view of a pillowcase or similar article showing my new design.

Fig. 2 is a rear view thereof.

The dominant feature of the design resides in a pillowcase having a detachable contrasting top and a matching border, all as shown.

I claim:

The ornamental design for a pillowcase or similar article, substantially as shown and described

NETTIE ROBINSON.
